UNITED STATES PATENT OFFICE

2,674,191

HYDRAULIC SPEED GOVERNOR FOR PRIME MOVERS

Richard Joseph Ifield, Dural, New South Wales,
Australia, assignor to Joseph Lucas Limited,
Birmingham, England

Application August 21, 1950, Serial No. 180,656

Claims priority, application Great Britain
August 22, 1949

5 Claims. (Cl. 103—11)

1

This invention relates to hydraulic governors for prime movers, such as jet propulsion engines, gas turbines and the like, the governors being of the kind adapted to control a liquid-operated servo mechanism for varying the output of a fuel supply pump or otherwise regulating the supply of fuel to the prime mover in response to variations of speed.

The invention has for its object to enable the speed at which the governor comes into action to be kept substantially constant over a wide range of variation of the rate at which the fuel is supplied to the prime mover.

The invention comprises the combination of a valve for controlling the servo mechanism, liquid-operable means for actuating the valve, the said means being in communication with a by-pass passage extending from the fuel supply system, a variable throttle adapted to control the flow of liquid through the by-pass passage, a dash pot responsive to the pressure of the liquid in the said passage for actuating the throttle, and means adapted to set up in the said passage a counter-pressure related to the speed of the prime mover.

The invention also comprises the combination with the means specified in the preceding paragraph, of an isolating valve for temporarily closing the by-pass passage while the prime mover is being started.

The accompanying drawing illustrates diagrammatically one embodiment of the invention.

Referring to the drawing, the liquid fuel supply pump there shown is of known form and comprises a rotor *a* having therein a plurality of bores each containing a spring-loaded plunger *b*, the rotor being contained in a housing *c*. Actuation of the plungers is effected by a swash plate *d*. For adjusting the obliquity of the swash plate there is provided a liquid-operated servo mechanism, which consists of a piston *e* connected to the swash plate by a rod *f*. The piston is slidable in a cylindrical chamber *g* and is loaded at one side by a spring *h*. The two ends of the cylinder are interconnected by a passage *i* containing a restricted orifice *j*, and the end of the chamber *g* remote from the spring is in communication with the discharge passage *k* of the pump. The end of the chamber *g* containing the spring *h* is in communication with a passage *m* leading to

2

the seating *n* of a valve *o*, which is carried by a lever *p* and loaded by a spring *q*. The parts *n*, *o*, *p*, *q*, are contained in a chamber *r* which is in communication with the pump inlet passage *2*, and which is separated from an adjacent chamber *s* by a flexible diaphragm *t* (or an equivalent piston), the diaphragm being loaded by a tension spring *u*. Movement can be transmitted from the diaphragm to the lever *p* by a stem *w*. The arrangement is such that when the valve *o* is closed, the spring *h* moves the piston *e* in the direction for increasing the pump output. When the valve *o* is open, the preponderating liquid pressure acting on the left-hand side of the piston moves the latter in the direction for reducing the pump output.

The chamber *s* is in communication with the pump housing *c* by way of a passage *x*, and in the rotor *a* are formed substantially radial passages *y* enabling the rotor to serve also as a centrifugal pump, so that liquid drawn from the inlet passage *2* of the fuel pump can be discharged into the housing *c* at a pressure determined by the rate of rotation of the rotor, the latter being driven by any convenient part of the prime mover to be supplied with liquid fuel.

In association with the arrangement above described there is provided a cylindrical chamber *3* containing a slidable throttle *4* co-operating with an orifice *5*, and the portion of the chamber *3* beneath the said orifice is connected by a pipe *6* to the above mentioned passage *x*. Also at a position above the orifice *5*, the chamber *3* is connected by pipes *7*, *8*, to the servo-cylinder *g* at the end which is in communication with the pump delivery passage *k*. The pipes *7*, *8*, are interconnected through an isolating valve to be hereinafter described.

The throttle *4* is arranged at one end of a rod *9* extending from a dash-pot piston *10* slidable in the chamber *3*, and having therein a restricted orifice *11*. The piston is attached to a tension spring *12* which is adjustable by a screw *13*.

The pipes *8*, *7*, and *6*, the passage *x*, the chamber *c*, and the passages *y* in the pump rotor *a* constitute a by-pass passage interconnecting the pump delivery passage *k* and the pump inlet passage *2*. The flow through the by-pass passage is controlled in part by the throttle *4* and in part by the counter-pressure exerted by the

centrifugal pump. It follows that the pressure in the chamber *s* is the sum of two variable pressures, one of them being related to the pressure in the pump delivery passage *k* and determined by the throttle 5, and the other being determined by the rate of rotation of the pump rotor *a*.

Assuming that the system is in a steady state, and working at the desired rate, the valve *o* will be open, and the passage through the orifice 5 will be restricted by the throttle 4 to an extent depending on the liquid pressures then acting on the diaphragm *t* and piston 10. A change in this pressure due to either a change of pressure in the fuel delivery system, or in the counter-pressure of the centrifugal pump, will result in a corresponding change in the condition of the valve *o*. Thus, with a fall in the speed of the pump rotor, the pressure in the chamber *s* will fall correspondingly. The effect of this is to cause the valve *o* to move to, or towards, its closed position and so cause the servo mechanism to vary the position of the swash plate and thereby increase the pump output. Meanwhile the said fall of pressure will also manifest itself at the throttle, and the spring 12 will gradually move the throttle to a more open position at a rate dependent on the dash-pot action associated with the piston 10. Eventually a new state of adjustment will be attained, and the liquid pressure in the chamber *s* will be restored to its previous amount, thus restoring the initial condition of the system. An increase of pressure above the previous amount in the fuel supply system will cause the throttle to move in the direction for reducing the flow through the part 5, causing the pump output to be reduced until the previous condition is restored.

To obviate loss of fuel from the supply system through the by-pass passage, while the prime mover is being started, there is provided the isolating valve above mentioned. In one convenient form this comprises a closure member 14 co-operating with a seating 15 to which is connected the pipe 8. The closure member is carried by a diaphragm 16 (or piston) in a hollow body part 17 which is divided by the diaphragm into two compartments. The lower compartment is connected to the pipe 7, and the upper compartment is connected by a pipe 18 to the pump inlet. Also the upper compartment contains a compression spring 19 which holds the closure member on its seating until the pressure in the pump delivery passage *k* reaches a predetermined amount. When the system is operating normally the closure member 14 is held off its seating by the fluid pressure acting on the diaphragm.

By this invention the desired action of the governor can be obtained in a very simple and reliable manner.

Having thus described my invention what I claim as new and desire to secure by Letters Patent is:

1. A hydraulic speed governor for a liquid operated servo mechanism for controlling the rate of supply of liquid fuel to a prime mover from a pump driven thereby comprising, in combination, liquid pressure responsive means arranged to actuate a valve for controlling said servo mechanism, a by-pass passage affording communication between the inlet and the discharge of the pump and having a connection with said pressure responsive means, a variable throttle for controlling liquid flow in said by-pass passage, means for creating in said by-pass passage a liquid counter-pressure related to and varying with the speed of the prime mover and opposed to the pump discharge pressure whereby the difference in said opposed liquid pressures actuates the pressure responsive means, means including a dash-pot responsive to the liquid pressure in the by-pass for actuating the variable throttle in a direction to restrict flow of liquid in the by-pass when the pressure therein rises and vice versa, said throttle actuation being effected at a controlled rate determined by the dash-pot, and an isolating valve in the by-pass passage for temporarily interrupting liquid flow

with the speed of the prime mover and opposed to the pump discharge pressure whereby the difference in said opposed liquid pressures actuates the pressure-responsive means, and means including a dash-pot responsive to the liquid pressure in the by-pass for actuating the variable throttle in a direction to restrict flow of liquid in the by-pass when the pressure therein rises and vice versa, said throttle actuation being effected at a controlled rate determined by the dash-pot.

5 2. A hydraulic speed governor according to claim 1, comprising an isolating valve in the by-pass passage for temporarily interrupting liquid flow therethrough while the prime mover is being started, and means operated by the pressure of liquid delivered by the pump for opening said isolating valve.

10 3. A hydraulic speed governor for a liquid operated servo mechanism for controlling the rate of supply of liquid fuel to a prime mover from a pump driven thereby comprising, in combination, liquid pressure responsive means arranged to actuate a valve for controlling said servo mechanism, a by-pass passage affording communication between the inlet and outlet of the pump and having a connection with said pressure responsive means, means forming a cylindrical chamber constituting part of said by-pass passage and having therein an orifice, a throttle valve movable in said orifice for controlling liquid flow in the by-pass passage, a dash-pot piston connected with the throttle valve and movable in the chamber under the pressure of liquid therein to actuate the throttle valve in a closing direction when said liquid pressure rises and vice versa, a spring acting on the piston, restricted passage means affording communication between parts of the chamber at opposite sides of said piston, and means for creating in the by-pass passage a liquid counter-pressure related to and varying with the speed of the prime mover and opposed to the pump discharge pressure whereby the difference in the opposed liquid pressures in the by-pass is employed to actuate the pressure responsive means.

15 4. A hydraulic speed governor according to claim 3, in which the means for creating the liquid counter-pressure comprise a centrifugal pump.

20 5. A hydraulic speed governor for a liquid operated servo mechanism for controlling the rate of supply of liquid fuel to a prime mover from a pump driven thereby comprising, in combination, liquid pressure responsive means arranged to actuate a valve for controlling said servo mechanism, a by-pass passage affording communication between the inlet and the discharge of the pump and having a connection with said pressure responsive means, a variable throttle for controlling liquid flow in said by-pass passage, means for creating in said by-pass passage a liquid counter-pressure related to and varying with the speed of the prime mover and opposed to the pump discharge pressure whereby the difference in said opposed liquid pressures actuates the pressure responsive means, means including a dash-pot responsive to the liquid pressure in the by-pass for actuating the variable throttle in a direction to restrict flow of liquid in the by-pass when the pressure therein rises and vice versa, said throttle actuation being effected at a controlled rate determined by the dash-pot, and an isolating valve in the by-pass passage for temporarily interrupting liquid flow

therethrough and comprising a chamber, a liquid pressure responsive member dividing the chamber into two compartments one of which forms a part of the by-pass passage and is provided with a seating, a closure member carried by the liquid pressure responsive member and arranged to co-operate with said seating, and a spring acting on the liquid pressure responsive member, the arrangement being such that pressure of the liquid delivered by the pump opens 10 the closure member of the isolating valve.
